UNITED STATES PATENT OFFICE.

HOWARD T. COOK, OF CRAFTON, PENNSYLVANIA.

MAIL-BAG AND BAG-SUPPORT.

1,027,524.

Specification of Letters Patent.

Patented May 28, 1912.

Application filed September 2, 1911. Serial No. 647,432.

To all whom it may concern:

Be it known that I, HOWARD T. COOK, a resident of Crafton, in the county of Allegheny and State of Pennsylvania, have invented certain new and useful Improvements in Mail-Bags and Bag-Supports, of which the following is a specification.

This invention relates to a mail collecting device, and has particular reference to a bag 10 of improved construction together with improved means for supporting the bag in open position, particularly within a letter-box, so that the letters drop directly into the bag, it being only necessary for the collector 15 to substitute an empty bag for the bag removed. This also avoids unnecessary and frequently injurious handling of a mass of letters incident to removing them from the box in the ordinary way.

20 While the bag and its supports are designed with special reference to letter-boxes, they may be employed wherever it is necessary or desirable to support a mail bag in open position.

25 Although the bag is constructed with special reference to coöperating with the novel supporting means, the design thereof is such that the mouth of the bag will close compactly and may be readily locked.

30 In the accompanying drawing, Figure 1 is a view in perspective of the top or mouth portion of a bag constructed in accordance with the invention, the same being shown open, and the supports shown applied thereto in dotted lines. Fig. 2 is a top plan of the mouth of the bag closed. Figs. 3 and 4 are vertical sections of a letter-box equipped with the invention, the views being taken at right angles to each other. Fig. 5 is a sectional detail of the mouth-frame, taken on line 5—5 of Fig. 1.

35 Referring to the drawing, 2 designates a letter-box of the type commonly used in office and other buildings for receiving letters from a mail-chute 3. The box itself may also be provided with a letter drop 4. In the present adaptation, opposite strap-like hangers 5 and 6 are shown depending from the top of the box, these hangers formed with 40 outturned extremities 5' and 6', respectively.

45 At least one of the hangers is formed of spring metal so that it may be deflected, as in dotted lines, Fig. 3, to facilitate placing and removing the bag, presently to be described. Hanger 5 may be rigid. Suspended 50 within the box by these hangers is the bag

or sack 7, which is provided with a folding top frame consisting of the opposite side bars 8 and the end bars 9, each of the latter being in two parts jointed together at 9', and with the extremities of the end bars hinged at 10 to the ends of side bars 8. The material forming sack 7 may be variously secured to this frame, in the present adaptation the material being fastened between the outer faces of the frame bars and strips 11, with the latter fastened to the bars by rivets 12 having the heads countersunk in the bars, as shown in Fig. 5. The jointed end bars of the frame fold compactly between the side 65 bars as shown in Fig. 2, and the space between the folded extremities of the end bars is occupied by the central enlargements 13 on the inner sides of bar 8, so that when the top frame is folded, as in Fig. 2, the bag is 70 completely closed and its contents may be secured by a hasp 14 and a lock 15. When the bag and its mouth-frame are open, the central enlargements 13 form ledges for resting on the outturned extremities 5', 6' of 75 the hangers, and by this means the bag is firmly supported in position to receive letters dropped from chute 3 or inlet 4. The bag may be readily positioned by first opening its top frame and then placing enlargement 13 of the side bars on extremity 5' of 80 the rigid hanger 5, and by deflecting hanger 6, as in dotted lines in Fig. 3, the bag may be raised to position, and upon releasing the hanger 6 the spring thereof forces it outward into engagement with the enlargement of the other side bar, the spring pressure of hanger 6 retaining the mouth-frame in engagement with both hangers, as will be understood. The spring hanger 6 is prefer- 85 ably arranged nearest the box door 2' and thus within convenient reach to be manipulated when placing and removing the bag. 90

95 While the improved bag and supporting means are designed with special reference 100 to facilitating the collection of mail matter from letter-boxes, the same may be variously utilized where mail bags are required to be supported in open position without departing from the invention.

105 I claim:—

110 1. In a mail bag support, the combination with a mail bag having a mouth, of a frame secured about the mouth to the mail bag and adapted to be opened, and a pair of depending strap hangers projecting into the mouth of the bag and having out-turned ex-

tremities engaging beneath the side bars of the frame to support the bag, one of said hangers being rigid and the opposite hanger being adapted to be flexed inwardly to release said frame therefrom.

2. In a mail bag support, the combination with a mail bag having an open mouth, of a closing frame secured about the mouth of the mail bag and having enlargements extending inwardly from the sides thereof, a pair of depending hangers projecting into the frame and having out-turned extremities

engaging beneath said enlargements to support the frame, one of said hangers being rigid and the other hanger being adapted for inward movement from the enlargement to release said frame and free the bag. 15

In testimony whereof I affix my signature in presence of two witnesses.

HOWARD T. COOK.
